Des. 237,011
Patented Sept. 30, 1975

237,011

SUBMERSIBLE PUMP

Rolf Stroberg, Langsjovagen 28, Alvsjo, Sweden, and Bo Ljunglof, Bredangsvagen 55, Skarholmen, Sweden

Filed Sept. 23, 1974, Ser. No. 508,000

Claims priority, application Sweden Mar. 25, 1974

Term of patent 14 years

Int. Cl. D15—02

U.S. Cl. D65—1 R

Fig.1.

Fig.2.

FIG. 1 is side perspective view of a submersible pump showing our new design;

FIG. 2 is a front perspective view thereof;

FIG. 3 is a top plan view thereof;

FIG. 4 is a bottom plan view thereof; and

FIG. 5 is a rear perspective view thereof.

We claim:

The ornamental design of a submersible pump, substantially as shown.
